MACHINE FOR OPERATING UPON THE SOLES OF BOOTS OR SHOES

Filed May 16, 1925

Fig.1.

INVENTOR.

Joseph Slater
By his Attorney,
Nelson N. Howard

UNITED STATES PATENT OFFICE.

JOSEPH SLATER, OF KETTERING, ENGLAND, ASSIGNOR TO UNITED SHOE MACHINERY CORPORATION, OF PATERSON, NEW JERSEY, A CORPORATION OF NEW JERSEY.

MACHINE FOR OPERATING UPON THE SOLES OF BOOTS OR SHOES.

Application filed May 16, 1925, Serial No. 30,744, and in Great Britain May 23, 1924.

This invention relates to machines for channeling or both channeling and trimming the soles of boots or shoes and is herein illustrated as embodied in a rounding and channeling machine of the type disclosed in United States Letters Patent No. 1,463,823, granted August 7, 1923, in the names of Johnson, Peterson and Popp. The present invention is to improve the construction and mode of operation of channeling or channeling and trimming machines for the purpose of adapting them for operations upon soles which have been temporarily secured in place upon McKay shoes as, for example, during the process of repairing such shoes. 55

Machines of the type referred to are particularly designed for operating upon the soles of welt shoes and to this end they are provided with a crease guide and a welt guide for engaging respectively within the welt crease and around the margin of the welt of a shoe to guide the shoe while it is being operated upon. Such machines are further provided with co-operating work-gripping members which are moved to and from each other and back-and-forth along the line of feed to impart a step-by-step feed movement to the work, and the rounding or trimming knife is relied upon to hold the work in successive positions to which it has been advanced by the feeding members while the said members make their return movements and while the channeling knife moves through its cutting stroke. Machines thus organized are not adapted to operate upon soles for McKay shoes because in such shoes there is no welt or its equivalent to be engaged by the welt guide and further, for the reason that at the time the channeling and trimming operations are to be performed there is no definite crease between the upper and the welt with which the crease guide may effectively co-operate for the purpose of guiding the shoe. Furthermore a McKay sole, when tacked to the last bottom prior to channeling and sewing, usually needs to be trimmed in some parts while the sole is in other places so narrow as to require no trimming. In other instances the shape and dimensions of McKay soles are such that no trimming whatever is required during the channeling operation. Wherever no trimming is required, the trimming knife of a rounding and channeling machine of the type above referred to, will not enter the work and consequently will not hold the work against displacement during the periods when it is released by the feeding members and while the channel knife is moving backwardly to make its cut. 100

With the foregoing in mind, one object of

To the accomplishment of this object, one feature of the present invention consists in the provision, in a sole-trimming machine, of means for trimming the edge of the sole of a lasted shoe, and a stationary work guide shaped and arranged to engage the upper of the shoe at a substantial height above the projecting margin of the sole of the shoe and to afford an extended bearing for the upper to locate the sole with respect to the trimming means as the shoe is moved past the work guide. In the embodiment of the invention herein illustratively shown as a rounding and channeling machine, means is provided for feeding a sole step-by-step past the rounding and channeling knives and means is also provided for holding the work during the intervals between the feed movements. The illustrated work-retaining means functions independently of the rounding knife and comprises a fixed gripper member, and a movable gripper member which co-operate at each upward or cutting stroke of the rounding knife, firmly to grip the margin of the sole of a shoe at a point closely adjacent to the plane of the cutting edge of the rounding knife and thus to hold the sole stationary between successive feed movements while the channel knife is making its cut. In this way the work is firmly held against the thrust of the channel knife irrespective of whether or not there is any material to be trimmed off by the rounding knife. The illustrative arrangement is further such that as the rounding knife approaches the limit of its downward or non-cutting stroke and the feed members are ready to impart another feed movement to the work, the movable gripper or work-retaining member is withdrawn from holding engagement with the work so as not to interfere with the feed thereof. 105

The invention further consists in the features of construction and in the combinations and arrangements of parts hereinafter described and claimed, the advantages of

which will be obvious to those skilled in the art from the following description, reference being had to the accompanying drawings, in which

5 Fig. 1 is a view, partially in side elevation and partially in section, of so much of a rounding and channeling machine as is necessary to illustrate the application of the present invention thereto; and

10 Fig. 2 is a detail side elevational view of the work guide and certain of the operative parts of the machine, illustrating the relation of the latter to the sole of a shoe which is being fed through the machine.

15 In the drawings, the invention is illustrated as embodied in a rounding and channeling machine having the same general construction as that shown and described in Letters Patent No. 1,463,823, hereinbefore referred to. As shown in Fig. 1, the illustrated machine is provided with co-operating work feeding devices comprising an oscillatory work supporting block or table 4 and a feed foot 6; and with operating instrumentalities comprising a channel knife 8 and a trimming or rounding knife 10; all of which are constructed, arranged and operated as fully described in said patent. The above-mentioned parts 20 are mounted upon a head or frame 12, to which is secured an adjustable block 14, and the illustrated machine is also provided with a fixed horizontal plate or support 16 which takes the place of the welt edge gage 30 of the machine shown in said patent. The plate 16 is arranged to overlie the upper surface of the projecting margin of the sole of a shoe which is being operated upon and it is provided with a cutting block 18 of soft 35 material which is embedded in the lower side of the plate and with which the rounding knife 10 is arranged to co-operate.

40 In a McKay shoe, such as that shown at 20 in Fig. 1, the outer sole 22 is merely secured temporarily at one or two points to the insole 24 in preparation for the channeling, rounding and sewing operations and as a result the outer sole and the upper are liable to gape apart, or at least 45 they can easily be forced apart by a crease guide of the type ordinarily employed in a rounding and channeling machine for guiding the work. Consequently, to adapt machines of the class herein referred to for 50 operation upon McKay shoes it is desirable to provide a work guide which is incapable of forcing its way between the upper and the sole of the shoe but which will be effective to guide the work. To this end, and 55 as illustratively shown in Fig. 1, there is 60 employed a work guide 26 of novel construction, the guide having a work-engaging portion which is arched about a horizontal axis extending parallel to the direction of feed of the shoe, the curvature being

such that the work guide is adapted to conform substantially to the bulging contour of the lower portion of the upper of a shoe, as shown at 28. The work guide is provided with a shank portion 30 which is 70 angularly disposed with respect to the work-engaging portion of the guide and which is secured by means of one or more screws 32 to the adjustable block 14, the forward extremity of the block 14 being 75 cut away and beveled as shown to enable the work guide to be located in the desired relation to the shoe. The curved work-engaging portion of the work guide 26 extends a substantial distance above the 80 projecting margin of the sole and is of sufficient height and width to afford a bearing surface of substantial area for the side of the shoe upper. As best shown in Fig. 2, the work guide 26 is slotted at 34 to permit the passage therethrough of the feed foot 6 and to provide ample clearance for the latter as it moves back and forth in feeding the work. It will be plain that the above-described improved work guide 26 85 cannot be forced inwardly between the upper and the sole as might be the case if a guide member in the nature of the usual crease guide were employed. Consequently 90 with a work guide of the illustrated construction there is no danger that the work will fail to be properly guided with respect to the channeling and rounding knives. 95

As hereinbefore set forth the soles of McKay shoes may require no rounding or trimming at all, or they may require rounding or trimming only at one or more portions of their margins. In the illustrated machine, the rounding knife will not be projected into the material of the sole at 100 those portions of the sole which do not need to be rounded and consequently will not be effective to hold the sole stationary between successive feed movements thereof so as to support the sole against the thrust of the 105 channel knife.

110 In the illustrated machine means is provided for holding the work independently of the action of the rounding knife between the feed movements of the work and thus to insure that the channeling operation will effectively be performed in the sole of a McKay shoe along such portions of the sole margin where there is no surplus material to be trimmed off by the rounding knife. 115 This result is accomplished by the provision of work-retaining means comprising a movable gripper member 36 which is adapted to co-operate with the fixed plate or gripper member 16 to grip or clamp the sole margin. The movable gripper member 36 is made 120 in the form of a plunger which is received for vertical sliding movement in an axial recess or bore 38 in a vertical slide bar 40 which constitutes a carrier for the rounding 125

knife 10. As shown in Fig. 2 the movable gripper member 36 has a width, considered along the line of feed of the work, corresponding to that of the rounding knife and it is located between the rounding knife and the work supporting table 4 and closely adjacent to the vertical plane of the cutting edge of the rounding knife. The gripper member 36 is thus arranged to engage the sole margin at a point just inwardly of where the sole margin is engaged by the rounding knife if there is any surplus material to be trimmed off. It will be plain therefore that if there is no material to be trimmed by the rounding knife the gripper member 36 will engage the sole substantially at the very edge thereof and will serve, in conjunction with the fixed gripper member 16, to exercise the normal work holding function of the rounding knife during intervals between the feed movements of the work, it being apparent that the rounding knife cannot perform any work holding function in cases where it does not actually enter the work.

To enable the work-retaining device to function as above described, the movable gripper member 36 is yieldingly urged upwardly by means of a compression spring 42 which is confined between the lower end of said member and the bottom of the recess 38 in the slide bar or rounding knife carrier 40. As shown, the upward movement of the gripper member 36 under the influence of the spring 42 is limited by engagement of a shoulder 44 on said member with the lower extremity of the rounding knife 10 to such an extent that the work-engaging face of the gripper member 36 is always spaced below the cutting edge of the rounding knife by a distance somewhat less than the thickness of a sole. This construction insures that the sole will always be clamped by the work-retaining means before the completion of the cutting stroke of the rounding knife and that the work retaining means will be operated to release the work at each non-cutting stroke of the rounding knife.

In the operation of the illustrated machine, when a rounding operation is being performed simultaneously with the channeling operation, the rounding knife 10 functions during the cutting stroke of the channel knife to hold the sole stationary as described in the before-mentioned patent. When, however, the channeling is taking place along a portion of the sole margin where there is no surplus material to be trimmed off by the rounding knife, the sole will be securely held by the work-retaining device comprising the gripper members 16 and 36 so that the work is effectively prevented from traveling back with the channel knife.

Having thus described my invention, what

I claim as new and desire to secure by Letters Patent of the United States is:

1. In a sole-trimming machine, means for trimming the edge of the sole of a lasted shoe, and a stationary work guide shaped and arranged to engage the upper of the shoe at a substantial height above the projecting margin of the sole and to afford an extended bearing surface for the upper to locate the sole with respect to the trimming means as the shoe is moved past the work guide.

2. In a sole-trimming machine, means for trimming the edge of the sole of a lasted shoe, work-feeding means, and a stationary work guide shaped to conform to the bulge of the upper of the shoe for guiding the shoe as it is being fed.

3. In a sole-trimming machine, means for trimming the edge of the sole of a shoe, and a stationary work guide arranged to engage the upper of a lasted shoe throughout a substantial area extending to a substantial height above the sole of the shoe and curved to conform substantially to the lengthwise curvature of the upper of the shoe.

4. In a rounding and channeling machine, a frame, means for feeding a shoe mounted on a last, and a work guide having a surface curved to conform to the contour of a substantial area of the upper of the shoe, and a shank portion rigidly secured to said frame.

5. In a rounding and channeling machine, the combination with a feed foot for engaging the upper surface of the projecting margin of a sole of a shoe, of a work guide arranged to engage the upper of the shoe throughout an area of substantial size and extending a substantial distance above the crease between the upper and the sole and having a slot through which the feed foot is arranged to operate to feed the shoe.

6. In a sole trimming machine, the combination with an intermittently operative trimming knife, of a cutting block arranged to co-operate with said knife in trimming the sole edge, means for feeding the work step-by-step past the knife, and work-retaining means operative to hold the work while the trimming and feeding means are inactive.

7. In a sole trimming machine, in combination, an intermittently operable trimming knife, a cutting block arranged to co-operate with said knife to trim a sole, means operable between successive operations of the trimming knife for feeding the shoe through the machine, and co-operating clamping devices immovable in the direction of work feed for gripping the sole margin to hold the shoe during the intervals between the feed movements.

8. In a sole rounding machine, in combination, a rounding knife, a cutting block

- arranged to co-operate with said knife to trim the sole of a shoe, means for feeding the shoe step-by-step past the rounding knife and the cutting block, means for operating upon the sole during the intervals between the feed movements, and means independent of the rounding knife and the feeding means for holding the shoe stationary during the operation of said means.
9. In a rounding and channeling machine, the combination with intermittently active rounding and channeling knives, of feed mechanism for advancing a shoe step-by-step, and yielding means independent of the rounding knife and the feed mechanism for holding the shoe while the channeling knife is active.
10. In a machine of the class described, in combination, means for imparting successive feed movements to a shoe, a knife for trimming the sole of the shoe, work-retaining members immovable relatively to each other in the line of work feed and constructed and arranged to grip the margin of the sole at a point closely adjacent to the plane of the cutting edge of the trimming knife to hold the shoe stationary between successive feed movements thereof, and a cutting block carried by one of said work-retaining members for co-operating with the trimming knife.
11. In a machine of the class described, in combination, means for imparting successive feed movements to a shoe, means for operating upon the sole of the shoe between successive feed movements thereof, a fixed gripper member for engaging one side of the projecting margin of the sole, and a movable gripper member for engaging the opposite side of the margin of the sole and co-operating with the fixed gripper member to hold the work stationary while it is being acted upon by said operating means.
12. In a machine of the class described, in combination, means for imparting a step-by-step feed movement to a shoe, means for operating upon the sole of the shoe between successive feed movements of the shoe, a fixed gripper for engaging the work, a movable gripper for co-operating with the fixed gripper to hold the shoe stationary while it is being acted upon by said operating means, and means for actuating the movable gripper to release the work prior to each feed movement of the shoe.
13. In a machine of the class described, in combination, means for imparting successive feed movements to a shoe, means for operating upon the sole of the shoe between said feed movements, a fixed gripper member for engaging one side of the projecting margin of the sole, a second gripper member movable toward and from the fixed gripper member for engaging the other side of the sole margin, a spring urging the movable gripper member into operative position, and means for reciprocating the movable gripper member to release the shoe.
14. In a machine of the class described, in combination, means for imparting successive feed movements to a shoe, a reciprocating carrier movable toward and from the sole of the shoe, a rounding knife mounted on said carrier, means for reciprocating the carrier to operate the rounding knife during the intervals between the successive feed movements of the shoe, and means including a gripper member mounted for sliding movement within the rounding knife carrier for engaging the margin of the sole to hold the shoe stationary between successive feed movements thereof.
15. In a machine of the class described, in combination, means for imparting successive feed movements to a shoe, a reciprocating carrier movable toward and from the sole of the shoe, a rounding knife mounted on said carrier, means for reciprocating the carrier to operate the rounding knife during the intervals between the successive feed movements of the shoe, means including a spring-pressed gripper member slidably mounted within the rounding knife carrier for engagement with the margin of the sole of the shoe to hold the shoe stationary between successive feed movements, and means on said gripper member to be engaged by the rounding knife during the non-cutting stroke of the latter for the purpose of releasing the hold of the work-retaining device upon the sole of the shoe.
16. In a machine of the class described, in combination, means for imparting successive feed movements to a shoe, a reciprocating carrier movable toward and from the sole of the shoe, a rounding knife mounted on said carrier, means for reciprocating the carrier to operate the rounding knife during the intervals between the successive feed movements of the shoe, means including a gripper member movably mounted on said carrier for engagement with the sole of the shoe, a spring urging said gripper member into holding engagement with the sole, and a shoulder on said member arranged for engagement with the rounding knife to limit the movement of the gripper member under the influence of the spring and to cause the gripper member to be retracted from the work by the rounding knife during the non-cutting stroke of the latter.
- In testimony whereof I have signed my name to this specification.

JOSEPH SLATER.
